UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

TRAIN CONTROL.

Application filed October 15, 1923. Serial No. 668,665.

This invention relates to speed control systems of the time-distance interval type, and to certain new devices forming major elements of such a system.

5 In providing speed control systems for railways, it is found that certain locomotives are at times used in passenger service and are at other times used for moving freight trains. For well-known reasons, a 10 train made up of freight cars (especially if loaded) is much more difficult to stop than is a passenger train, so that, other conditions remaining the same, it is found necessary to restrict the speed of a freight train more 15 than a passenger train in order to bring it to a stop, or to a predetermined low speed, before reaching a danger section. Also, a safe and proper stop of a freight train provided with the usual type of air-brake equipment 20 requires a greater degree of skill because of the varying conditions of grade, slack between cars, and the like, under which a brake application must be made, and for which ordinary automatic apparatus can not 25 provide.

With the above and other considerations in mind, it is proposed in accordance with the present invention to provide a system of train control in which control influences are 30 transmitted from the trackway to a moving vehicle through an intervening air gap, which is designed and constructed in accordance with the closed circuit principle, so that the interruption of any circuit causes an automatic application of the brakes; to provide a circuit arrangement including a circuit for energizing a primary exciting or field coil, the field of which is an essential for the proper operation of the system and is 35 checked against an open, and the depreciation of the current flow in the circuit due to a failure of the source of supply, or the like.

Further, the circuit arrangement proposed 40 is such that a short between turns in this exciting coil or a shunt around this coil will produce an effect upon the system which causes an automatic brake application. Also, the decrease of current through the exciting 45 coil, due to an increase of contact resistance of certain contacts in series therewith, produces a similar effect, which also causes more sensitive operation of the system so as to assure the transmission of a control influence when passing an active trackway de-

vice. Next, the proposed car-carried equipment consists of a circuit arrangement which is checked so that an open or a detrimental decrease in current flow in any circuit and the shorting or detrimental shunting of the 60 exciting coil produces an automatic brake application.

As a further object and purpose of the present invention, it is proposed to provide a time-element device to control certain circuits in a certain sequence if initiated, in which the time cycle may be adjusted for freight or passenger service as required; to provide a brake valve actuator which may be attached to the usual engineer's brake 70 valve which if actuated causes an effective and unpreventable brake application when set for passenger service, and which actuates the usual engineer's brake valve in a manner so that the engineer may forcibly prevent or forestall an automatic application of the brakes when adjusted for freight service, so that the engineer may make a partial 75 brake application to bunch the slack which may be followed by a full application of the 80 brakes when used in freight train service.

A still further object of the present invention contemplates the provision of a time-element device which will actuate the engineer's brake valve if two successive control influences are transmitted from the trackway in less than a predetermined period of time, in which the time constant of the device may be adjusted for passenger and freight service respectively, this adjustment being 85 interlocked with the brake valve actuator so that the time-element device and the brake valve actuator must both be adjusted for either passenger or freight service.

Other objects, purposes, and characteristic 90 features of the invention will appear as the description progresses.

In describing the invention in detail, reference will be made to the accompanying drawings, in which:—

Fig. 11 illustrates an exploded view of the various essential elements of the time-element device, certain responsive devices and a circuit arrangement of the train control system embodying the present invention.

Structure of engineer's brake valve actuator and control valve.

Referring to Figs. 1 to 6, inclusive, of the drawings, an engineer's brake valve actuator embodying the present invention is shown applied to the usual engineer's brake valve which is controlled by a suitable electro-pneumatic valve EPV. The body of the usual engineer's brake valve has been illustrated at 1 as provided with the usual cap 2, from the top of which projects the usual valve stem 3. This valve stem 3 is squared at the end to receive the usual engineer's brake valve handle or the actuator embodying the present invention, as desired.

The actuator comprises a casing C terminating in oppositely disposed cylinders 4 and 5, and having a semi-circular extending base consisting of two arcuate pieces 6 and 7 connected by two vertical ribs 8 (see Figs. 5 and 6). In the top of this casing C is a hole in which is pivotally supported change-over mechanism for setting up means so as to cause an unpreventable brake application for passenger service or to cause a permissive brake application for freight service, as desired. This change-over mechanism comprises a change-over plate 9, to opposite sides of which are riveted a cam 10 and a lever 11, respectively, by rivets as shown. This change-over plate 9 is also provided with a downwardly extending portion which

forms a journal for pivotally supporting suitable apparatus presently to be described. In order to provide proper lubrication about this journal, an oil hole has been provided, as shown, which is normally closed by a screw 12.

This passenger to freight change-over plate 9 is provided with a skirt to which is fastened a contact comprising a ring 13 of insulating material, to which is fastened a contact segment 14 by suitable rivets as shown (see Fig. 5), said segment extending partly around the insulating ring (see Fig. 1). The back of the actuator casing C (see Fig. 1) is provided with a rectangular opening, which is normally closed by a conduit outlet 15 through which suitable wires are brought from a flexible conduit 16 (Fig. 5). This conduit outlet 15 has screw fastened thereto a block of insulating material 17 to which are riveted spring contact fingers 18 by eyelets 19, the wires 20 being passed through these eyelets and fastened to said fingers.

With the change-over handle 11 in the passenger position, as shown, the contact fingers 18 are bridged by the contact segment 14. If, however, the change-over handle 11 is moved to the other extreme or freight service position, the segment 14 is out of contact with one of these contact fingers 18, thereby interrupting a circuit including these wires 20.

The change-over handle may be locked in either of its extreme positions to perforated projecting lugs, as shown, (see Fig. 1) by a padlock, seal or the like, so that it may either be set to the proper positions and locked there, only by persons authorized to do so, or if sealed it may be changed by the engineer by breaking such seal, which serves as a tell-tale, as desired.

A valve actuator sleeve AS, having a square hole in the bottom thereof and fitting on the valve stem 3, has its upper end pivotally supported on the downwardly projecting journal portion of the change-over plate 9. This actuator sleeve AS has integral therewith oppositely disposed arms 21 and 22, respectively, (see Figs. 3 and 4) the functions of which will be more fully explained hereinafter. The arm 22 is provided with a hole in the side thereof forming a pocket to receive the end of a compression coil spring 23 (see Fig. 4); and the other end of this spring seats in a similar hole in a latch 24, pivotally supported between the ears 25 extending from the actuator sleeve AS, so that the latch is yieldably held in the position shown.

The actuator sleeve AS has pivotally supported thereon a gear sector 27, which is limited for endwise movement by a shoulder on the actuator sleeve AS and by the change-over cam 10 (see Fig. 2). This gear sector

- 27 has a headed unlatching pin 28 slidably supported in the web of this gear sector; and this pin is urged upward by a spring 29 (see Figs. 2, 3 and 5) against the cam 5 surface of the cam plate 10. It should be noted that this cam plate 10 has part of its periphery cut away (see Fig. 3), so that the head of the unlatching pin 28 rides against the surface of the cam plate 9 for 10 all positions of the actuator under freight service conditions, but rides on the cam portion of the change-over cam 10 for all positions of the actuator under passenger position of the change-over handle 11. In other words, the unlatching pin 28 extends from the bottom of the gear sector when the apparatus is set for passenger service, but does not project from the bottom thereof when it is set for freight service.
- 15 20 This gear sector 27 is actuated automatically, and in the particular embodiment of the invention shown is actuated by a differential piston operating mechanism, comprising a large piston 31 contained in the large cylinder 5 and a small piston 32 contained in the small cylinder 4. These pistons are provided with the usual piston rings, gaskets, and clamping devices well known in the art. These pistons 31 and 32 are supported on the ends of a rack 33, and are adapted to move endwise by pressure in the cylinders 4 and 5 until they engage the screw plugs 34 or 35 of the cylinders 4 or 5, respectively, and are prevented from 25 30 turning by reason of the engagement of the rack 33 with the gear sector 27. The cylinder 4 is connected to main reservoir pressure, as shown by MR, by a pipe 36, whereas the large cylinder 5 may be connected to main reservoir pressure or to atmosphere through a pipe 37 by a suitable electro-pneumatic valve EPV to be described hereinafter. From the gear sector 27 projects a 35 40 downwardly extending lug 40, which is of a length so that it may engage the arm 21 extending from the actuator sleeve AS.
- 45 On the lower end of the actuator sleeve AS is pivotally supported a handle plate HP (see Fig. 2), which is limited in its upward movement by a shoulder on the actuator sleeve AS and by engagement with an inwardly extending flange 42 extending from the casing C. This handle plate HP is held up in position by a retaining plate RP, having two radially extending legs 43 and 44 fastened to the actuator casing C by cap screws as shown (see Figs. 2 and 6).
- 50 55 60 This handle plate HP is provided with an upwardly extending semi-circumferential rib 46 (see Figs. 2, 3 and 4), which has its one end tapered so as to cooperate with the end of the latch 24 while the apparatus is in its normal condition. This handle plate HP is also provided with an upwardly extending lug 47, which under normal con-
- ditions engages the arm 22 extending from the actuator sleeve AS (see Figs. 4 and 5). This lug 47 does not extend far enough to interfere with the lug 40 projecting down from the gear sector 27, so that both the lug 40 and the lug 47 may engage this arm 22 (see Fig. 5) without interference.
- 65 It should be noted that movement of the rack 33 from the right toward the left causes movement of the gear sector 27 in a counter-clockwise direction, and that a certain amount of movement of this gear sector is possible before the projecting lug 40 on this gear sector engages the arm 22 on the actuator sleeve AS. This amount of lost motion is provided so that the engineer's brake valve handle 50, which is integral with the handle plate HP, may be moved from the normal running position as shown to the release position (see Fig. 4) without causing engagement of the arm 22 with the lug 40. If the gear sector is actuated in a counter-clockwise direction by the rack 33 and associated pistons, the valve proper of the usual engineer's brake valve will assume the service position as the piston 31 engages the screw cap 35. If, however, this movement of the automatic apparatus moves very fast, the inertia of the parts might possibly carry the valve proper beyond the service position; and in order to avoid this contingency, a suitable stopping or counter-acting mechanism has been provided.
- 70 75 80 85 90 95 100 105 110 115 120 125 130
- In the embodiment of the invention illustrated, a stop arm 51 is pivotally supported by a pin between ribs 52 extending from the back of the casing C. This stop arm 51 is of the peculiar shape shown (see Fig. 4), and is provided with a limiting pin 53 which limits the movement of this arm 51 in the clockwise direction by reason of engagement of this pin 53 with the upstanding rib 46 of the handle plate HP. As the rack 33 and associated parts are moved to the brake applying position, the piston 32 engages the rounded portion of the arm 51 and urges this arm to the position shown in the drawings (see Figs. 3 and 4) by a force depending on main reservoir pressure and the size of the piston 32. As the actuator sleeve AS is moved in the counter-clockwise direction by the rack 33, the pin 54 riveted into the arm 22 extending from the actuator sleeve AS engages the cam portion shown at 51¹, and is opposed and resisted from further movement by reason of this stop arm 51. If desired, the engineer may, however, force the actuator sleeve AS to the emergency brake applying position; and in order to avoid overthrowing of the valve proper beyond the emergency position by the engineer when the handle plate HP is unlocked (as will more clearly appear hereinafter), the stop arm 51 has been provided with a hook 51² for limiting the move-

ment of the sleeve AS beyond the emergency brake applying position.

As heretofore mentioned, the small cylinder 4 is continuously connected to the main reservoir and the larger cylinder 5 is at times connected to main reservoir pressure, and is at other times connected to atmosphere. This arrangement is used so that with the same pressure in both of the cylinders, the larger piston 5 overpowers the smaller one and causes the rack to be moved toward the righthand position as shown; and if pressure is released from the large cylinder by connecting it to atmosphere, the pressure in the small cylinder 4 causes an automatic actuation of the apparatus. It is thus noted that the force for actuating the apparatus is always present by reason of the presence of main reservoir pressure in any air-brake system when in use, so that the two cylinders with differential pistons are constructed on the side of safety, that is, a failure of air pressure in the cylinder 5, which is the cylinder that is controlled, will cause an automatic application of the brakes, failure of pressure in the small cylinder 4 being highly improbable and practically impossible.

In the particular construction shown, the electro-pneumatic valve EPV for controlling the flow of main reservoir pressure to the small cylinder 4 or for connecting the cylinder to atmosphere, comprises an electro-pneumatic valve consisting of a top or valve portion, and a bottom or actuating portion. The valve portion comprises a chamber having three compartments 60, 61 and 62, respectively. The middle compartment 61 is connected to the cylinder 5 by a pipe 37, whereas the top compartment 60 is connected to the main reservoir by a pipe 64, and the bottom compartment 62 is connected to atmosphere by a port 65. The partitions between the several compartments are provided with tapered openings forming valve seats to cooperate with valves 66 and 67, respectively. These valves 66 and 67 are rigidly secured to a valve stem 68 slidably supported in the screw plug 69, in a manner so that when one valve is closed the other is open. This valve stem 68 is normally urged downward by a spring 70 contained in the bottom compartment between the partition and a collar 71 pinned to the valve stem.

The actuating portion of the electro-pneumatic valve EPV comprises an iron-clad electro-magnet, consisting of a magnetic casing 75 supported on the main casing of the valve in any suitable manner. This magnetic casing 75 is closed by a cover 76 of non-magnetic material, and contains a solenoid 77 in which is disposed a core 78 connected to the lower end of the non-magnetic valve stem 68. On the lower extreme

end of the core 78 is a disc-shaped armature 79, which in its normal energized position is disposed adjacent the solenoid 77.

Operation of engineer's brake valve actuator and EPV.

Assume now that the electro-pneumatic valve EPV is deenergized by suitable automatic apparatus on the vehicle, possibly because of danger traffic conditions ahead. Deenergization of the winding 77 causes the valve stem and associated valves to assume the lower position, whereby the valve 66 cuts off main reservoir pressure from the compartment 61 and the valve 67 connects this compartment 61 and in turn the cylinder 5 to atmosphere through the port 65. As the fluid pressure in the large cylinder 5 decreases, due to the venting thereof to atmosphere, main reservoir pressure in the small cylinder 4 moves the pistons 31-32 and rack 33 toward the left, thereby moving the gear sector 27 in a counter-clockwise direction. A certain amount of idle movement of the gear sector, for reasons here tofore explained, will first take place.

Just before the lug 40 depending from the gear 27 strikes the arm 21 projecting from the actuator sleeve AS, the unlatching pin 28, by reason of the fact that it is in its depressed position because the change-over handle 11 is in the passenger service position, rides under the cam surface of the change-over cam 10 and engages the upwardly extending part 24 of the latch 24, thereby actuating this latch, compressing the spring 23 and causing uncoupling between the actuator sleeve AS and the handle plate HP as far as counter-clockwise rotation of the cam sleeve AS is concerned. Just after this unlatching has taken place, the depending lug 40 of the gear sector 27 engages the arm 22 of the actuator sleeve and continued movement of the rack causes the actuator sleeve to be moved to the service brake applying position, whereupon the piston 31 strikes the screw cap 35 to establish the ultimate position of the automatic apparatus. With the pistons 31-32 in their ultimate brake applying position, the piston 32 engages the stop arm 51 so that the momentum due to the inertia of the parts can not cause the actuator sleeve AS to be moved beyond the service position, this by reason of the pin 54 and the arm 22 of the actuator sleeve engaging with the cam portion of this stop arm 51.

If now the engineer wishes to effect an emergency application of the brakes, he may move the handle 50, thereby causing the handle plate HP to follow up the actuator sleeve AS and when reaching the service position causing the lug 47 of the handle plate HP to engage the arm 22 of the actuator sleeve. By applying a considerable force, the engineer may cam the stop arm 51.

toward the right (see Figs. 3 and 4) in opposition to main reservoir pressure acting against the arm 51; whereby if the pin 54 has passed off of the cam portion 51¹, no further opposition due to the stop arm 51 exists until the emergency position has been reached. Just a little beyond the position at which the handle plate forms an operative connection with the actuator sleeve AS by engagement of the lug 47 with the arm 21, the latch 24 will no longer be engaged by the unlatching pin 28, thus again locking the handle plate to the actuator sleeve AS to allow the valve to be moved by the handle through a certain limited angle. For instance, if the engineer should wish to release the brakes, he may move his handle in a clockwise direction and carry with it the actuator sleeve AS to the service position. As soon as the service position is reached, the latch 24 is no longer engaged by the unlatching pin 28 so that the operative connection between the handle plate and the actuator sleeve is again broken, and movement of the engineer's brake valve handle 50 to the running or release position produces no effect because the valve itself will be held in the service position by the rack 33 through the medium of the lug 40. Let us assume now that the apparatus is again in its normal condition, as shown in the drawings, and that the change-over handle 11 is moved to the other extreme or freight service position. With this handle 11 moved to the freight service position, a circuit is interrupted due to disengagement of the contact segment 14 with one of the contact fingers 18, for reasons more fully described hereinafter. Also, this movement of the change-over handle causes the change-over cam to assume a position so that the head of the unlatching pin 28 no longer is held in its depressed position, but may assume its upper position and ride on the under surface of the change-over plate 9 for all positions of the gear sector 27. If now the gear sector is moved in a counter-clockwise direction, in a manner as heretofore explained, by the automatic shifting of the rack 33, the unlatching pin 28 does not strike the top portion 24¹ (see Fig. 5) of the latch 24, so that no unlatching between the actuator sleeve AS and the handle plate HP takes place. It is thus noted that, with the freight set-up, the engineer may oppose the force exerted on the actuator sleeve by holding the handle against movement. The diameters of the cylinders 4 and 5 are so chosen that the excess diameter of the cylinder 5 over that of the cylinder 4 is sufficient to overcome friction of the various parts and move the apparatus to the normal position, as shown, with main reservoir pressure in both of these cylinders; and the cylinder 4 is large

enough to assure movement of the mechanism to the brake applying position in case the other cylinder 5 is connected to atmosphere, but is small enough so that the engineer may effectively prevent an automatic application of the brakes when his handle is latched to the actuator sleeve AS by reason of the change-over handle 11 being in the freight service position, by forcibly opposing movement of the valve by the automatic apparatus. 70 75

The handle 50 integral with the handle plate HP is provided with the usual latch 55 spring pressed outwardly by a compression coil spring 56 contained in the handle. This latch 55 is adapted to engage suitable notches in the quadrant 2¹ on the cap 2 of the usual engineer's brake valve for the purpose of facilitating the movement of the brake valve to the different positions. A suitable thumb trigger 57 is pivotally supported from the handle 50 by a pin; and to this thumb trigger 57 is pivotally secured a tapered plug 59, which is adapted to be forced into a conical opening in the latch member 55. Normally, this thumb trigger 57 is pressed outwardly by a compression coil spring 58 supported as shown; and if the engineer wishes to increase the force acting on the latch 55 in a direction to engage notches in the quadrant 2¹, he may press his hand or thumb against the thumb trigger 57, thereby forcing the tapered plug 59 in the conical opening and holding the latch 55 projected out of the handle. 90 95 100

This construction is provided so that when the change-over mechanism of the brake valve actuator is in the freight service position, and the engineer wishes to hold off an application in order to bunch the slack of the train or the like, he may force the handle back to the running position temporarily, or he may hold it there permanently if he wishes, to avoid an automatic application of the brakes. In order that the engineer may know at all times whether he is in the service or lap position, both of these positions being defined by a single notch on the cover of the engineer's brake valve, the thumb trigger 57 has been provided to hold the latch 55 more forcibly projected. That is, the latching effect in the service-lap notch may be made more pronounced by pressing the thumb trigger 57. 110 115 120

Time-element device.

This device is preferably carried on the tender of the locomotive, together with the relays and associated devices, in a suitable weather-proof and spring-supported casing where it can be readily inspected. 125

Structure.—Generally speaking, the time-element device, which is an important ele- 130

ment of the present invention, comprises a balance wheel mounted for rotation and urged to a certain intermediate position by a suitable spring but held in one extreme 5 position by an electro-magnet; whereby if the electro-magnet is momentarily deenergized, the balance wheel is started on a cycle of rotation and will rotate beyond the neutral position, thus tensioning the 10 spring in the opposite direction, after which it will return to almost its initial position, thus completing a cycle of operation after which it can again be held by the electro-magnet. The oscillation of the balance 15 wheel opens and closes circuits in certain sequence, whereby a suitable train control device is operated only if two successive impulses are received in less than a certain interval of time corresponding to one oscillation of the balance wheel. The time interval or cycle may be changed by loading and unloading the balance wheel in a simple 20 and efficient way.

More specifically, this time-element device 25 TE (see Figs. 7 to 10) comprises a cylindrical casing K, having a cover 85 with an inserted glass panel 86, and a detachable base plate 87. Near the top of the casing is supported a spring housing SH 30 containing a ball bearing 88 of the usual unitary assembled type. This spring housing SH is stationary under normal operating conditions of the apparatus, but is pivotally supported for rotation about a vertical axis 35 for reasons more fully described hereinafter. The base plate 87 is provided with a similar ball bearing 89. The ball bearings 88 and 89 support a shaft 90 for rotation about a vertical axis; and to this shaft 40 90 is connected a balance or inertia wheel 91. In the particular embodiment of the invention illustrated, this balance wheel 91 is fastened to the shaft 90 by a spring 45 pressed friction slip clutch for the purpose of allowing a certain amount of slippage if the shaft is suddenly accelerated or decelerated.

In the particular construction shown, this clutch comprises a pair of discs 92 and 93 50 spring pressed together by being engaged by one end of a compression coil spring 94, which has its other end supported by a flanged washer 95. A disc of friction material 96 is interposed between the hub of 55 the balance wheel 91 and the plates 92 and 93, respectively. The upper plate 92 is adjustably secured to the shaft 90 by a threaded connection as shown, and is provided with axially extending teeth so that it may 60 be locked in any adjusted position by a cross pin as shown, for reasons more fully described hereinafter.

The main vertical shaft 90 is shouldered 65 near its upper end to support a spring anchoring hub 98, which has a plurality of

axially extending holes in its end face, any one of which may receive a pin 99 riveted to the contact operating sleeve 100 splined to the shaft by a cross pin 101. It will thus be noted that, when the contact operating sleeve 100 is moved upward on the shaft 90, the spring anchoring hub 98 may be rotated with respect to the shaft to any one of various adjusted positions, after which the contact operating sleeve 100 may be slid back in splined engagement with the shaft and thereby fixedly secure the hub 98 to the shaft 90. 70 75

As heretofore mentioned, the shaft 90 is biased to a predetermined position by a suitable spring, similar to the hair-spring of a watch. In the particular embodiment illustrated, this spiral spring 104 has its inside end fastened to the spring anchoring hub 98 by a pin 105, and has its other end riveted to the inside of the spring housing SH by a rivet 106 (see Fig. 9). By reason of the adjustable connection of the spring anchoring hub 98 to the shaft 90, the normal position of said shaft and the balance wheel 91 80 85 90 may be adjusted with respect to the spring housing SH. In order to change the effective length of the spring 104, a clamp 107 embracing the spring (see Figs. 8 and 9) is provided which is adjustable about the periphery of the spring housing SH by teeth projecting from this clamp which are adapted to engage the saw teeth formed in the top edge of the spring housing SH, in which position this clamp is held by a cover 95 screw-fastened to this housing SH, thus forming the well-known washboard adjustable means for changing the effective length of the spring 104. The mechanism of the time-element device TE thus far described 100 105 comprises parts corresponding in many respects to the well-known balance wheel used in chronometers.

Holding magnet.—In addition to the balance wheel 91, the shaft 90 is weighted by an armature 108 supported from the shaft and a counter-balance bracket 109 supported directly opposite this armature (see Figs. 8 and 10). This armature 108 is under normal conditions held in the position shown 110 in the drawings by a starting or holding magnet HM. This holding magnet HM comprises a pair of cores 110 terminating in enlarged pole pieces 111, which are fastened in a non-magnetic cover plate 112 secured to the side of the casing K. The other ends of these cores 110 are threaded and are magnetically connected together by a back yoke 113 secured in place by nuts as shown. 115 120

On each of these cores 110 is a coil 114, these coils being connected in series in a suitable circuit, more fully described hereinafter. Secured to the side of the pole pieces 111 by screws as shown (see Fig. 8) 125 is a bridge 115 of non-magnetic material. 130

This bridge 115 is cross-drilled and counter-bored, and contains a spring pressed residual pin 116, which is limited in its movement in both directions as shown. This residual pin 116, when fully depressed into the counterbored cavity, projects outside of the bridge 115 a sufficient distance to maintain a small air gap between the armature 108 and the pole pieces 111, for the purpose of preventing an excessive amount of residual magnetism which might hold the armature in the attracted position when the electro-magnet HM is deenergized. The spring 104 is secured to the spring anchoring hub in such a way that it tends to move the armature 108 to a position where it is displaced between 100 and 120 degrees from its normal attracted position.

It will thus be noted (referring particularly to Fig. 10) that deenergization of the coils 114 allows the spring-pressed residual pin 116 to start off the armature, after which the spring 104 will carry it to its biased position. The inertia of the rotatable parts will, however, carry the armature substantially again as far (that is, 200 to 220 degrees) from its normal attracted position, thereby tensioning the spring 104 in the opposite direction. After this position of the armature has been reached, the spring 104 will again return the armature back within a very short distance of the residual pin 116. If, by the time the armature reaches this position, the holding electro-magnet HM is again energized, the armature 108 will again be attracted and held in its attracted position as shown in the drawings. In other words, a momentary deenergization of the holding magnet HM allows the balance wheel 91 and associated parts to complete one oscillation, after which they may be again locked into the normal position and held there by the electro-magnet HM, ready for another oscillation.

Operating contacts.—In order to maintain one circuit closed during normal conditions of the apparatus and close another circuit for a time near the mid-stroke of a cycle of operation of the time-element device, two contacts operable by the shaft 90 are provided. One of these contacts, conveniently called the normally open contact, and the other contact, conveniently called the normally closed contact, are substantially the same and for convenience the description of one will suffice for both; and for convenience like parts of these contacts have been given like reference characters, the exponent "a" being applied to the reference character of the normally open time contact.

In the particular construction shown (see the righthand contacts of Figs. 7 and 9), the side wall of the casing K is provided with a large rectangular opening directly

over the holding magnet HM, over which is fastened a cover plate 120 of insulating material, supporting binding posts 121 and 122, respectively. The binding posts 121 have pivotally secured thereto a contact finger 123, spring-pressed outwardly by a spring 124, and is limited in its outward movement by an adjustable stop nut 125. To the end of this contact finger 123 is riveted a contact piece 126 of non-fusible contact metal. This contact finger 123 has extending ears, between which is pivotally secured a metallic roller 127. The other binding post 122 has adjustably fastened thereto a stationary contact 128, preferably so of highly refractive conducting material, such as carbon, or the like, which is adapted to be locked in place by a lock nut.

To the contact operating sleeve 100 is fastened a sector of insulating material 130, to which is riveted a cam or arcuate piece of metal 131. The contact operating sleeve 100 is held in its lower splined position by another contact operator 132 which is clamped to the shaft 90 by a cap screw 133. To this latter contact operator is fastened an actuator 134 secured to a hub 132 but insulated therefrom by an insulating strap 135. Under normal conditions of the apparatus, the contact actuator 134 engages with the roller 127 and maintains the contact finger 123 in engagement with the stationary contact 128; whereas the arcuate piece 131 is not in engagement with the roller 127 except when the balance wheel is substantially in the middle of an operating cycle, and therefore contact finger 123^a is normally out of engagement with the stationary contact 128^a.

By looking at Figs. 7 and 9, it will be noted that if the holding magnet HM is momentarily deenergized, the balance wheel 91 and associated parts will complete a cycle of operation during which the contact finger 123 is released from the stationary contact 128 to open a circuit by movement of the mechanism in a counter-clockwise direction as shown by the arrows. When the balance wheel 91 has substantially reached its ultimate position, the arcuate segment 131 will engage the roller 127^a and for a time complete a circuit by reason of the contact finger 123^a engaging the stationary contact 128^a, after which the balance wheel is turned to a position to again open the contact finger 123^a, and when it has substantially completed its stroke, will again complete the circuit including the contact finger 123 and the stationary contact 128.

Change of timing for freight and passenger.—In order to prolong the time necessary to complete the cycle heretofore mentioned, suitable means have been provided for weighting or loading the balance wheel 91 so that the time necessary to accelerate

and decelerate the total weight is increased. In the particular construction shown, a cup-shaped change-over weight 140 of magnetic material, having a downwardly extending 5 V-shaped flange 140¹ adapted to engage a V-shaped groove in the balance wheel 91, is disposed above said balance wheel. This weight 140 forms an armature of a suitable change-over magnet CM, which, if energized, 10 raises the weight from the balance wheel 91, but if deenergized, allows said weight to rest on the balance wheel 91, thereby increasing the mass to be oscillated.

This change-over magnet CM, in the particular construction shown, comprises an inverted cup-shaped piece of magnetic material 141, forming the external magnetic circuit of an iron-clad electro-magnet, which is fastened by screws or the like to lugs on 15 the main casing K. This inverted cup 141 is provided with a threaded opening near the center thereof, in which is threaded a hollow core 142 surrounding the shaft 90 of the time-element device. This core 142 is 20 provided with an enlarged circular pole piece 142¹, which is rabbeted to support a ring 143 of non-magnetic material. In the annular pocket formed by the cup 141 and the core 142 is contained a coil 144 for controlling the change-over magnet CM. In order to prevent the residual magnetism of the change-over magnet CM from maintaining the change-over weight 140 of magnetic material in its raised position, even when 25 the change-over magnet is deenergized, a residual plate 145 of non-magnetic material is interposed between these two devices. As heretofore explained, the clutch plate 92 may be adjusted to various elevations by 30 removing a lock pin and turning this plate upon the shaft 90. This construction is provided so that the position of the balance wheel 91 with respect to the change-over magnet CM may be varied so as to facilitate 35 the adjustment of the air gap between this magnet and the change-over weight 140, the ring 143 of non-magnetic material being provided so that impregnating compound, or similar substance used for saturating the 40 coil 144, can not work its way between the residual plate 145 and the core 142.

From the construction of the apparatus just described, it is apparent that energization of the change-over magnet CM reduces 45 the effective weight of the timing mechanism to the extent of the weight 140, for the reason that said weight will be held firmly against the residual plate 145 and will not interfere or retard the operation of the timing mechanism; whereas if this magnet CM is deenergized, the weight 140 will wholly rest on the balance wheel 91, and will increase the effective weight of the timing mechanism to this extent.

60 *Reset devices.*—The mechanism thus far

described comprises the essential parts of the time control mechanism as far as operating conditions are concerned. If, however, two successive control impulses are received in less than the time cycle of the 70 time-element device, as hereinafter explained, the armature 108 will stop in the intermediate position; and it is necessary to provide a convenient way of restoring the timing mechanism to its normal position, 75 this resetting apparatus being preferably operable only from the ground.

In the particular construction shown, the spring housing SH is pivotally secured in a cross-piece 148 (see Figs. 8 and 10) fastened to the casing K; and this spring housing is biased to one extreme position, so that the stop lug 149 projecting from the bottom thereof engages the cross-piece 148 by a spring 150, this spring having its one end 80 connected to a pin 151 adjacent to the lug 149, and its other end secured by a screw 152 to a flange extending from the cross-piece 148. This spring 150 develops sufficient torque to maintain the spring housing SH 85 in its normal position as shown, regardless of the position of the armature 108 or the tension which may exist in the spring 104 under normal operating conditions.

To the lower extreme end of the hub extending from the spring housing SH, is secured a pinion 153 by a dowel screw 154. This pinion 153 is in operative engagement with a rack 156 guided by an arm 112¹ extending from the non-magnetic cover 112. 90 To the extreme end of this rack 156 is fastened a piston 158 provided with the usual packing, or the like. This piston 158 is 95 slidably supported in a cylinder 112² integral with the non-magnetic cover plate 112. 100 The end of the cylinder 112² is closed by a screw plug 159, to which is connected a pipe 160 adapted to be connected to suitable fluid pressure, such as the main reservoir pressure of the usual air-brake system, designated 105 MR.

Referring particularly to Fig. 10, let us assume that the holding magnet HM is energized but that the armature 108 is in its neutral or intermediate position, substantially 110 degrees to the left of the position shown in the drawings. If now main reservoir pressure is applied to the cylinder 112², the piston 158 and rack 156 are moved to the left and turn the spring housing SH in 115 a clockwise direction. Since the armature 108 is connected (at least yieldably) to the spring housing SH, the armature will naturally also move in a clockwise direction and is attracted by and engages the pole pieces 120 of the holding magnet HM when the rack reaches its ultimate position and the lug 149 engages the other end of the cross-piece 148. 125 As main reservoir pressure is released and the pipe 160 is again connected to atmos- 130

phere, the spring 150 returns the spring housing SH to its normal position, thus tensioning the spring 104, because the armature 108 is maintained in its attracted position.

5 *Reset contacts.*—In order to make and break certain circuits for resetting purposes during the resetting operation just mentioned, a double contact normally open reset switch DR shown on the left side in Fig. 7 has been provided, this switch being closed substantially at the end of the operating stroke of the reset mechanism. This double contact normally open reset switch DR is constructed substantially the same as the operating contacts heretofore described (the corresponding parts being designated by the same reference numbers and an exponent "c"); but is provided with an additional contact 160 adapted to cooperate with 10 a stationary contact 161 electrically connected to a binding post 162. This double contact reset switch DR is provided with an insulating roller 163, which is engaged by the switch operator 164 riveted to the spring housing SH (see Fig. 7). It should be noted that this switch operator 164 is of such a shape that it does not interfere with the operators for the operating contacts, nor with the make-before-break contact to be 15 presently described. It will be noted that movement of the spring housing SH through an arc of substantially 170 degrees in a clockwise direction causes the switch operator 164 to engage the roller 163 to put this double reset switch DR in its operative position.

In order to make and break circuits in overlapped relation at the beginning and at the end, respectively, of the resetting operation, a make-before-break contact MB has been provided (see Fig. 9). This make-before-break contact comprises a pivotally supported finger 166 to which are riveted movable spring contact fingers 167 and 168. These spring contact fingers 167 and 168 are biased outwardly, and are limited in such direction by a double headed pin 169. The contact spring 168 is normally in engagement with a contact on the binding post 170. The contact spring finger 167 is adapted to engage a contact connected to the binding post 171 when the finger 166 is in its other extreme position. The finger 166 itself is connected to a binding post 172, and is biased and limited in its movement substantially the same as the contacts heretofore described. The contact finger 166 is held in the normal position by an insulating roller 173, pivotally secured to the spring housing SH, which engages an arm 174 extending from this finger 166.

By looking at Figs. 7 and 9, it is apparent that a reset operation, comprising a movement of the spring housing SH in a clockwise direction through substantially

170 degrees back again to its normal position, causes the two contacts of the contact mechanism DR to be closed substantially throughout this cycle of operation, and causes the make-before-break switch MB to 70 be moved to an abnormal position and maintained there until the resetting operation is completed. The purpose of these resetting contacts will be more fully described in connection with the operation of the system 75 shown in Fig. 11.

Reset valve.—As above explained, the time-element device is restored to normal, after operation thereof due to excessive speed, by admitting and exhausting pressure 80 from the cylinder 112². This is preferably done by manual operation of a reset valve accessible only from the ground. A simplified construction of reset valve RV for this purpose is shown in Fig. 11. With the 85 valve RV in the position shown, the cylinder 112² is connected to atmosphere; but when said valve is manually shifted to the dotted line position, pressure from the main reservoir is supplied to said cylinder, with 90 the results above explained.

Other car-carried devices.

In addition to the brake valve actuator and the time-element device already described, the car-carried apparatus includes a control relay CR, a secondary relay SR and a brake control relay BR which have been conventionally illustrated in Fig. 11. These relays are all of the tractive type, and are provided with balanced armatures supported on vertical pivots so that jar and vibration will not have a tendency to disturb them from their normal position or prevent their actuation when they should respond. The control relay CR is made so as to be exceptionally quick acting, and is provided with light contacts for controlling small currents; whereas the relays SR and BR, while also quick acting, are provided with heavier moving parts capable of controlling larger currents. In practice, these relays are resiliently supported in a suitable heavy spring supported casing, so that a large part of the vibratory disturbances are 100 absorbed by this casing; but these details are 105 not material to the present invention.

The car-carried apparatus also includes a cutout device CO for automatically cutting off energy of the car-carried apparatus when the railway vehicle on which it is mounted is out of service. This cutout device CO comprises a cylinder 180 provided with a piston 181 normally held in its upper position by pressure below this piston supplied 110 directly from the main reservoir of the braking equipment, a compression coil spring 182 being provided between the upper side of this piston and the end of the cylinder 180, so that if the main reservoir pressure falls 115 120 125 130

to a predetermined low value the piston 181 will move downwardly, thereby moving the contact 183 from the stationary contacts (conventionally shown by arrows) and interrupting the main supply circuit of the car-carried apparatus.

- If an engine and tender equipment equipped with the car-carried apparatus, just described, is laid up at the end of its 10 run, in a roundhouse, or the like, the main reservoir pressure will usually gradually leak off because the steam to the air compressors is shut off. As the main reservoir pressure falls below a predetermined value, 15 the spring 182 of the cutout device CO moves the piston 181 down and opens the contact 183, whereby current is cut off of the various car-carried devices automatically. Before the engine can go back into 20 service, main reservoir pressure must be brought up to said predetermined value whereby the automatic cutout switch again is closed to energize the several circuits of the car apparatus.
- 25 The car-carried apparatus also includes a car element or impulse receiver L, comprising a U-shaped core 184 constructed of a good quality of laminated magnetic material terminating in enlarged pole pieces 185.
- 30 One of the legs of this core is surrounded by a primary coil P for producing a large magneto-motive-force in this core and a corresponding field of flux emanating from the pole pieces 185; and the other leg is surrounded by a secondary coil S for controlling the control relay CR in a manner more fully described hereinafter.

Trackway apparatus.—The train control system embodying the present invention is 40 adapted to be used in connection with any one of the well-known types of signaling systems, or in connection with suitable manually controlled trackway devices, and for convenience the system has been shown in 45 connection with a typical commercial signaling system of the closed track circuit type. Although the system may be used in connection with distinctive aspect color light or position light or semaphore signals, for 50 convenience it has been illustrated in connection with a signaling system of the semaphore type. The usual track rails 187 are divided by insulated joints 188 to form divided blocks. Since the various blocks of the 55 system are the same, the exist end of the block J and the entrance end to the block J only have been illustrated. The exit end of each block is provided with a suitable source of energy, conventionally shown as a battery 189, and the entrance end to each block is provided with a suitable track relay 190. These 60 track relays 190 control the signals Z and have been shown conventionally without illustrating their well-known operating mechanism or control circuits.

Each of the blocks is provided with a plurality of pairs of track elements, only one pair of which has been shown. The first track element T of each pair comprises a U-shaped core 191 constructed of a high 70 grade of magnetic material, preferably laminated, and terminating in enlarged pole pieces 192. A suitable distance in advance of this track element T there is provided a similar but controllable track element T^a, 75 which comprises a similar core 191 provided with a coil 193 on the back yoke thereof, which coil is normally closed in a circuit of low resistance, for reasons more clearly described hereinafter.

Adjacent each of these pairs of track elements is provided a repeater track relay 194, which has one of its terminals connected to the terminal C of a suitable source of energy, such as a battery, and has its other terminal connected to a line wire 195, which is connected through a front contact 196 of the track relay 190 of the next block in advance to the other terminal B of the battery.

These track elements or inductors T and T^a are preferably located at one side of the track, with their pole pieces a few inches above the level of the top of the track rails; and the receiver L is carried on the locomotive or other vehicle in position to pass over 95 and come in superimposed relation to the track inductors T and T^a.

The locomotive or other railway vehicle has been conventionally illustrated by the axles 200 and 201; and on this vehicle are 100 mounted the various elements of the car-carried system in suitable cooperative relation. On this railway vehicle is provided a suitable source of energy, such as one or more batteries, having a terminal B and 105 having their other terminal connected to a common return wire C.

Operation.

Normal conditions.—Under normal conditions of the apparatus, the primary coil P and the electro-pneumatic device EPV are connected in series, the device EPV being shunted by a discharge resistance 202. The circuit for energizing this primary coil P 110 connected in series with the brake control device EPV may be traced as follows:—beginning at the terminal B of the car-carried battery wire 203, contact 183 of the cutout device CO, wires 204, 205 and 206, primary 115 coil P, wires 207, 208 and 209, make-before-break contact BM, wires 210 and 211, front contact 212 of the brake control relay BR (which is placed in its energized position and maintained energized in a manner described hereinafter), wire 213, winding 77 of the device EPV, wire 214 back to the common return wire C. The flow of current in this circuit maintains the device EPV 125 energized and energizes the primary coil P 130

to an extent to provide a suitable magneto-motive-force in the car element L.

The control relay CR is connected in series with the secondary coil S of the car element L; and for reasons more clearly described hereinafter, the source of energy for normally maintaining the control relay CR energized is derived by connecting it in multiple with the primary coil P, so that the voltage applied to the secondary coil and control relay CR is always proportionate to the voltage drop across the primary coil P. The circuit for energizing this control relay CR and secondary coil S may be traced as follows:—beginning at the terminal B of the battery, wire 203, contact 183 of the cutout device CO, wires 204, 205, 215 and 216, front contact 217 of the brake control relay BR, wires 218 and 219, front contact 221 of the control relay CR, wires 222 and 223, winding of the control relay CR, wire 224, secondary coil S, wire 225 to the junction point between the primary coil P and the electro-pneumatic valve EPV, namely, the wire 208.

The secondary coil S is, therefore, connected in series with the control relay CR by a partial circuit including the front contact of this control relay forming a shunt around the primary coil P, so that if a voltage is induced in this secondary coil S which reduces the flow of current through the control relay CR, this relay will drop its armature, thereby opening its stick contact and its stick energizing circuit.

If the control relay CR is in its normal energizing position, a circuit is completed for energizing the secondary relay SR:—starting from the terminal B, wire 203, contact 183, wires 204, 205, 215 and 216, front contact 217 of the brake control relay BR, wires 218 and 219, front contact 228 of the control relay CR, wires 229 and 230, lower winding of the secondary relay SR, wires 231 and 232, front contact 233 of the secondary relay SR, wire 234 back to the common return wire C.

With the control relay CR in its energized position, an energizing circuit for the lower coil of the brake control relay BR is completed. This circuit is the same as the circuit for the lower coil of the secondary relay SR from the terminal B of the battery up to and including the wire 229, from whence it comprises wire 235, lower winding of the brake control relay BR, wire 236 connected to the common return wire C. In other words, the control relay CR is connected in a stick circuit including its front contact and when in its energized position maintains the lower windings of the relays SR and BR energized, this circuit for the relay BR being non-stick but that for the relay SR being a stick circuit including the front contact 233 of this relay SR.

With the secondary relay SR in its energized position, as just explained, an energizing circuit for the time starting magnet TM is completed which may be traced as follows:—beginning at the terminal B, 70 winding 114 of the time starting magnet, wire 238, front contact 233 of the secondary relay SR, wire 234 back to the common return wire C. With the time starting magnet energized, and the time-element device 75 actuated to its normal position during the preceding resetting operation as heretofore mentioned, this time element device is maintained in its normal wound up condition.

Although the brake control relay BR is 80 adapted to be maintained in its energized position if the lower winding is energized by the circuit heretofore traced, another or auxiliary circuit for maintaining this relay in its energized position is energized by the 85 following circuit under normal condition of the apparatus:—wire 203, contact 183 of the cutout device CO, wires 204, 205, 215 and 216, front contact 217, wires 218 and 240, normally closed contact 123 of the time-element device, wires 241 and 242, the upper winding of the brake control relay BR, wire 243 to the junction point between the primary coil P and the brake control device EPV, namely, the wire 208. 90

It is thus noted that if the control relay CR is momentarily deenergized, thereby momentarily deenergizing the lower winding of the brake control relay BR, this relay will not assume its deenergized position if 100 the time-element device is in the normal condition, because its upper winding is energized through the circuit just traced. Since, however, deenergization of the secondary relay SR deenergizes the time starting magnet TM, and since the secondary relay SR is also controlled by the control relay CR, it is evident that the normally closed contact 123 will be opened shortly after the time starting magnet TM is deenergized, 110 so that the brake control relay BR will be deenergized a short time after the control relay CR is energized, unless this control relay is again reenergized.

Passing first inductor T.—Let us assume 115 that the railway vehicle illustrated equipped with the car-carried apparatus shown in Fig. 11 in its normal condition, is moving along the block I with the block J unoccupied. As the vehicle moves along the block I, the car-carried element passes directly over the track element T in a manner so that the pole pieces 185 and 192 come in cooperative relation through a small air gap. This cooperation of the car element L 120 with the track element T reduces the reluctance of the magnetic circuit including the car element, so that a sudden increase of 125 magnetic flux through the secondary coil S takes place, this sudden increase of flux be- 130

ing probably due to both a diversion of flux from leakage paths and an increase of the total flux passing through the primary coil P on account of the reduced reluctance of the 5 magnetic circuit including the car element L. Also, as the car element L recedes from the track element T, the flux again changes back to its normal value. This sudden increase and decrease of the flux induces a 10 voltage in the secondary coil S, similar to a single cycle of alternating current. The control relay CR is connected in circuit in a manner so that the first wave of this single cycle of electro-motive-force is in a direction 15 to reduce the flow of current to the control relay CR, thereby momentarily deenergizing the control relay CR. Since the control relay CR is connected in a stick circuit, it remains deenergized until reset 20 through the back contact controlled by the secondary relay SR.

With the control relay CR in its deenergized position because its stick contact 221 is open, deenergization of the secondary relay SR, controlled by the front contact 228 of the control relay CR, is effected. As soon as the secondary relay SR assumes its deenergized position, a pick-up circuit is closed for the control relay CR, which may 25 be traced as follows:—beginning at the terminal B of the battery, wire 203, contact 183 of the cutout device CO, wires 204, 205, 215 and 216, front contact 217 of the brake control relay BR, wires 218 and 240, normally closed contact 123 of the time-element device, wires 241 and 246, back contact 247 of the secondary relay SR, wires 248, 249 and 223, winding of the control relay CR, wire 224, secondary coils of the car element L, wire 225 back to the wire 208 forming a junction point between the primary coil P and electro-pneumatic valve EPV, so that the control relay CR again assumes its energized position whereby its 30 stick contact 228 is closed to complete the stick circuit heretofore traced.

With the control relay CR again energized, the secondary relay SR would again have been energized had its stick circuit including front contact 233 not been broken. The secondary relay SR having been deenergized, as just explained, has interrupted the circuit for the time starting magnet TM so that the time-element device has started on 50 its cycle of operation, the control relay CR having, however, again been picked up through the circuit heretofore traced before the time-element device moved far enough to open the normally closed contact 123 of the time-element device. The time-element device now swings in the counter-clockwise direction, as indicated by the arrows on the timing contact actuators, until it has moved an angle of substantially 210 degrees, at 55 which point its inertia has been again trans-

ferred to the spring 104, after which it returns almost entirely back to its original position depending upon the friction of the device.

After the time-element device has moved 70 in a counter-clockwise direction through substantially an arc of 180 degrees, as shown by the distance of movement of the cam 131 necessary until it strikes the roller 127^a, a pick-up circuit for the secondary relay SR 75 is completed by the following circuit:—wire 203, contact 183 of the cutout device CO, wires 204, 205, 215 and 216, front contact 217 of the brake control relay BR, wires 218 and 219, front contact 228 of the control 80 relay CR, wires 229 and 230, the lower winding of the secondary relay SR, wires 231 and 250, normally open contact 123^a of the time-element device, wire 251 back to the common return wire C. The completion 85 of this circuit causes the secondary relay SR to assume its energized position, after which the stick circuit heretofore traced through the front contact 228 of the relay CR is again completed, thereby permanently sticking up this secondary relay SR and in turn again energizing the time starting magnet TM of the time-element device.

As the balance wheel of the time-element device on the return swing carries the armature 108 within a small distance of the pole pieces of the starting magnet TM, the armature 108 comes within the influence of the flux emanating from the pole pieces of this starting magnet so that it is attracted to its 90 normal position, thereby holding said armature and the balance wheel in the normal position.

It should especially be noted that through 95 this cycle of operation the brake control relay BR has not been deenergized, because the normally closed contact 123 of the time-element device has temporarily maintained this relay BR energized while the control relay CR was deenergized; and this control relay CR is immediately picked up by the back contact of the secondary relay SR, so that the EPV is maintained energized if a single impulse is received by the secondary coil S of the car element L while the time-element device is normal. It should be understood that the contact operator or cam 134 is made of such length that there is time for the relay CR to be reenergized upon dropping of the relay SR after the starting 100 of the balance wheel which also occurs upon deenergization of the relay SR.

Briefly summarizing the various steps in the operation of the car equipment when a single impulse is received at the first active inductor of a pair and while the time-element device is in its normal or initial condition, the control relay CR is first momentarily deenergized by the induced voltage 115 in the secondary coil S, and by reason of 120

its stick circuit this relay automatically remains deenergized until restored. The dropping of the relay CR interrupts one of the normally closed stick or holding circuits for the relay BR and also deenergizes the relay SR, the relay BR being held up at this time by its other stick or holding circuit (including stick contact 217) through the normally closed contacts 123 of the time-element device. The dropping of the relay SR, however, at once starts the time-element device, and likewise causes reenergization of the control relay CR by the pick-up circuit through the back contacts of said relay SR and the contacts 123 of the time-element device, the contacts 123 remaining closed long enough for the relay CR to again pick up. As soon as the relay CR is reenergized, and this happens before the contacts 123 of the time-element device open, the first stick circuit for the brake control relay BR is re-established and this relay is maintained energized in spite of the opening of the contacts 123. At this stage in the operation, the relay CR, previously dropped, has been restored, the time-element device is in operation, and the relay BR is maintained energized solely by its stick circuit through the front contact of the relay CR, the relay SR being still deenergized. As the balance wheel of the time-element device swings, contacts 123^a are momentarily closed, energizing the lower winding of the relay SR, which is instantly energized and then maintained energized by its stick circuit through the front contact of the relay CR. With the relay SR reenergized, the magnet TM of the time starting device is energized and acts to catch and hold the balance wheel as it swings back to its initial or normal position.

The important point to be recognized is that the brake control relay BR, after the reception of the first impulse and so long as the time-element device is operating and until the balance wheel returns to its normal initial condition, is maintained energized solely by its stick circuit through the front contact of the control relay CR, with the obvious result that, if the control relay CR is deenergized prior to the return of the balance wheel to its initial condition, the relay BR is totally deenergized and causes a brake application.

Passing second inductor. Clear conditions.—Let us assume that the vehicle continues to move in the normal direction of traffic, as indicated by the arrow, and that it passes by the track element T^a. Since the block J is unoccupied and the relays 190 and 194 are energized, the coil 193 on the core of the track element T^a is closed in a circuit of low resistance by reason of the fact that contact 194¹ is in its raised position. Under these conditions, only a very low single cycle of voltage is induced in the sec-

ondary coil S of the car element. The reason for the induction of such a small voltage in a secondary coil S when the bucking coil 193 on the track element is closed in a circuit of low resistance, is believed to be due to the counter-magneto-motive force set up by the current induced in this coil 193.

As the car element first comes into communicating relation with the track element, a slight change of flux takes place through the track element, thereby causing the flow of a heavy current in the coil 193. This current, by well-known principles of alternating current, is in a direction to oppose the magneto-motive-force producing it, so that only a very small change of flux through the track element takes place causing a similar small change of flux in the car element L. In other words, the passage of a car element over a track element having its bucking coil closed in a circuit of low resistance does not cause an appreciable change in the reluctance of the magnetic circuit including the car element, so that only a small change of flux through the secondary coil S and the induction of a similar low voltage in this coil takes place. Since the present train control system is constructed on the premise that the reception of two control influences in less than a predetermined time causes a brake application; and since only one control influence has been received in passing over the pair of trackway elements shown in the block I, the train can proceed without an automatic application of the brakes for reasons just explained.

Passing second active inductor at proper speed.—Let us assume now that the train is moving through the block I in a manner just described except that the block J in advance is occupied by another train. Under this condition of the block J, the track relay 190 and the line relays 194 (only one being shown) are in their deenergized condition, and the second track element of each pair has its coil open circuited so that it will have the same effect on a car-carried apparatus as does the track element T.

Let us also assume that the train is moving at a speed less than the restrictive speed enforced by the pair of track elements T and T^a shown. As the car element L passes by the track element T, the control relay CR is deenergized, thereby deenergizing the secondary relay SR and starting the time-element device upon its cycle of operation. Before the time-element device has moved far enough to open its normally closed contact 123, the back contact 247 of the secondary relay SR has closed a pick-up circuit, thereby reenergizing the control relay CR through its stick circuit and again completing the circuit for the lower coil of the brake control relay BR, so that this relay

BR is maintained up regardless of the momentary deenergization of the control relay CR and later opening of contact 123 for a period of time, all as above described.

- 5 Since the train is moving at a slower rate than the permissive or limiting speed set up by the spacing of the track elements T and T^a , that is, by the time the time-element device will have reached its normal position, and by reason of the reenergization of the time starting magnet TE before this second track element T^a is reached, the brake control relay BR is not deenergized so that the same cycle of operation may again take place at the second track element T^a , as just described, without causing an automatic application of the brakes.

Passing second inductor at excessive speed.—Let us assume now that the train is moving at an excessive speed in the block I when the block J is occupied by another train. As the train in question passes the track element T, the time-element device is initiated upon a cycle of operation in a similar manner as heretofore explained. It should be noted that the normally closed timing contact 123 is open through substantially the entire cycle of movement of the time-element device. As the train moves over the second track element T^a , a similar impulse is received by the secondary coil S causing deenergization of the control relay CR. The dropping of the secondary relay SR in this event will not pick up the control relay CR, because the pick-up circuit for the control relay CR including the back contact 247 of the secondary relay SR includes the normally closed contact 123 of the time-element device, so that the control relay CR is left in its deenergized position. Also, the deenergization of the control relay CR deprives the lower winding of the brake control relay BR of energy, and the open condition of the time contact 123 deprives the upper winding of the brake control relay BR of energy. This brake control relay BR, therefore, assumes its deenergized position, thereby breaking the main control circuit, including the front contact 217, of all the relays, and also breaking the energizing circuit of the electro-pneumatic valve EPV, causing actuation of the brake valve actuator in a manner heretofore described, to apply the brakes.

Resetting after automatic brake application.—After the train has been brought to a stop by the automatic brake application, the control apparatus may be reset to normal and the brakes released by a suitable valve RV only accessible from the ground, so that it may only be operated when the train is not in motion. This resetting operation consists of operating the valve RV which applies pressure back of the piston 158 in the cylinder 112^a, thereby operating the rack and

in turn moving the spring housing SH in a clockwise direction (as viewed from the top) so as to bring the armature 108 in communication with the pole pieces of the time starting magnet TM. The initial movement 70 of the rack 156 causes the make-before-break contact mechanism MB to close the contact 167 and open the contact 168. Closure of the contact 167 completes a circuit for energizing the primary coil P, not including in series the device EPV. This circuit may be traced as follows:—beginning at the terminal B of the battery, wire 203, contact 183 of the cutout device CO, wires 204, 205 and 206, primary coil P, wires 207, 208 80 and 209, front contact 167, wire 255 back to the common return wire C connected to the other terminal of the battery.

During this resetting operation, it will be observed that current is supplied to the primary coil P at the time the relay CR is re-energized. This arrangement is employed, rather than restoring the relay CR and thereafter applying current to the primary coil P, because it has been found that the application of current to the primary coil P and the resultant increase in flux tends to cause the relay CR to open on account of the voltage induced in the secondary coil S. By applying current to the primary coil 95 concurrently with the energization of the relay CR, this possibility is avoided; and on account of the make-before-break contacts 167 and 168, the current through the primary coil P is maintained without interruption, being shifted from a direct connection to battery over wire 255 to the electro-pneumatic valve EPV.

Near the end of the stroke of the rack 156, the switch operator 164 strikes the roller 163 105 to operate normally open reset switch DR, thereby closing pick-up circuits for the control relay CR and the secondary relay SR, respectively. These circuits comprise wire 203, contact 183 of the cutout device CO, 110 wires 204, 205, 215 and 256, movable contact 123^a, wires 257, 249 and 223, winding of the control relay CR, wire 224, secondary coil S, wire 225 back to the terminal of the primary coil P which is connected directly to the common return wire C, through the make-before-break switch MB, this make-before-break switch being in its abnormal resetting position; and the pick-up circuit for the secondary relay SR is the same as the 115 one just traced to and including the movable contact 123^a, from whence it comprises wire 258, upper winding of the secondary relay SR, wire 259 back to the common return wire C.

The closure of the two pick-up circuits just traced causes the control relay CR and the secondary relay SR to assume their energized position, thereby reenergizing the time starting magnet TM, and also closing an 130

energizing circuit for the lower coil of the 5 brake control relay BR. Also, at the end of the stroke of the rack 156 during the resetting operation, the armature 108 is brought into communicating distance with the pole pieces of the time starting magnet TM, but since this magnet is not immediately energized at the end of the stroke, the armature is not attracted until the secondary 10 relay has been picked up by the completion of the pick-up circuits just traced. The closure of the time contact 123 at the end of the resetting stroke completes the energizing circuit for the upper winding of the brake control relay BR heretofore traced, so that both 15 windings of the brake control relay BR are again energized. Although the three relays CR, SR and BR are again energized and the time-element device is in its normal position, the device EPV is still deenergized, for reasons presently to be described. This 20 is because the resetting apparatus is still in its active position, holding the make-before-break contact BM in its abnormal position and energizing the primary coil P by connecting it directly across the battery, instead of connecting it in series with the EPV as 25 heretofore explained.

If now the resetting valve RV is put back 30 to its normal position, pressure is exhausted from the cylinder 112² and the spring 150 returns the spring housing SH to its normal position, thereby again moving the make-before-break contact BM to its normal position, thus again connecting the device EPV 35 in series with the primary coil P and re-energizing it, whereby the engineer may manually release the brakes in a manner as heretofore explained in connection with the 40 brake valve actuator. It should especially be noted that the device EPV is not energized while the resetting mechanism is in its active resetting position. This arrangement is employed so that the engineer may not 45 permanently leave his resetting mechanism in its active condition and thereby permit the train to proceed along the trackway, that is, the device EPV may only be energized when the resetting mechanism is in its 50 normal inactive condition. After the train control apparatus has been restored to its normal condition, the engineer may proceed subject to the speed limits that may be enforced by a succeeding pair of inductors.

55 *Change-over for freight and passenger.*—Let us assume now that the car-carried equipment illustrated is to be used for freight service. This is accomplished by moving the passenger-to-freight set-up handle 11 to the dotted freight service position, whereby the brake valve actuator moves the 60 brake valve in a manner so that the engineer may forcibly oppose and prevent an automatic brake application. This movement of

the handle 11 also interrupts the circuit for 65 the magnet 144 of the change-over mechanism CM, thereby releasing the additional weight 140 of magnetic material (serving as an armature) and causing it to rest upon the balance wheel 91 so as to increase the momentum of this wheel, thereby changing the time constant of the time-element device so that the train must consume a longer period of time in moving between successive track 70 elements of a pair when pulling a freight 75 train than when the engine is operating in passenger service.

It should be noted that the engineer can 80 not set his brake valve actuator into the permissive or freight position without also putting the time-element device in its freight or slow speed condition. To a large extent, this in itself is protection against the possibility of the engineer setting the apparatus 85 for passenger service when it should be set for freight service, because the engineer, by moving the handle 11 to obtain passenger speed limits, also sets the brake valve actuator so that the engineer can not prevent an 90 automatic application by holding the engineer's brake valve in the running position; and it is believed that, rather than having an 95 unpreventable automatic application of the brakes take place while pulling a freight 100 train, the engineer would prefer to allow the permissive speeds intended for freight trains to be enforced. In other words, he would prefer to be provided with means for holding off an automatic application, rather than be permitted to move at a higher speed without the provision of such forestalling or preventing facility, so that the seal or locking means heretofore mentioned may be omitted, if desired.

105 *Failure on side of safety.*—Although intermittent train control systems inherently function on the open circuit principle, in that an impulse from the trackway is necessary to produce a stopping influence, the 110 present train control system is substantially of the closed circuit type, because the magnetic quality of a body along the trackway is relied upon for the transmission of such a control influence, and this characteristic is 115 unvarying and always present. An open circuit in the coil 193 of a trackway device Ta puts this trackway device in its active condition, so that it is constructed on the side of safety.

120 Referring now to the manner in which the normally closed circuit principle, or failure on the side of safety, has been applied to the car-carried apparatus, it will be noted that the electro-pneumatic valve EPV is normally energized and requires a certain amount of current in its windings to maintain it closed and prevent the automatic operation of the brake valve actuator. Con-

sequently, if the battery or other source of current should fail, there is an immediate brake application due to the deenergization of the electro-pneumatic valve EPV.

- 5 In the particular type of system illustrated, it is important for the reception of a satisfactory stopping impulse that the primary coil P should not only be energized, but should be energized to a sufficient extent 10 to provide a flux field strong enough to produce an effective induced voltage in the secondary coil by the action of the track inductors, with due allowance for variations in air gap and other factors. While the intensity of flow of current through the primary coil P is checked to a large degree by 15 the inclusion of the electro-pneumatic valve EPV in series therewith, this valve opening when the current falls below a certain value, 20 the arrangement of the circuits of this invention further assures sufficient current flow through the primary coil P for satisfactory operation, particularly on account of the way in which the relay CR is energized. As 25 previously stated, the relay CR, with the secondary coil S in series therewith, is connected in multiple with the primary coil P; or, in other words, the relay CR is energized with a strength of current corresponding to 30 the drop in potential across the primary coil P. Consequently, if the voltage across the primary coil P and the current flow therein should decrease, particularly on account of dirty or bad contacts in the primary circuit, 35 the control relay CR is energized with less current and more readily opens its contacts. Similarly, if the insulation should break down and some of the turns of the primary coil be short-circuited, the resistance of the 40 primary coil as a whole would be decreased, the potential drop across it become lower, and the energizing current for the relay CR drop below the point where the relay CR would hold closed its contacts. If the primary coil should become wholly open-circuited, the electro-pneumatic valve EPV 45 would be deenergized and the brakes automatically applied, the resistance of the secondary coil S and the relay CR being so high 50 that there would not be sufficient current flow to maintain said electro-pneumatic valve sufficiently energized. It may be stated here that, in one particular organization found satisfactory in practice, the primary coil P has a resistance of some 20 55 ohms, the secondary coil 350 ohms, the relay CR 1800 ohms, and the electro-pneumatic valve EPV 4 ohms, the normal primary current being something like one ampere. 60 These values are of course merely illustrative, it being understood that the various devices may have different resistances or may be constructed to perform their desired functions satisfactorily, so long as the appropriate relation is maintained to provide 65

the protection against open circuit and depreciation of primary current.

It will be observed that the relay CR is normally energized, and if its energizing circuit should open, or if its energizing current should drop below the critical value, this relay opens its contacts, and the time-element device is automatically started. Since the relay CR, under the conditions assumed, will fail to pick up upon dropping of the relay SR, after opening of the contacts 123 of the time-element device, both windings of the relay BR are deenergized, its contacts opened, and the electro-pneumatic valve EPV deenergized to automatically apply the brakes.

Similarly, the brake control relay BR is normally energized; and if both of its energizing circuits should open, the brakes are immediately applied. If the circuit energizing the upper winding of the relay BR only should become open, the brakes are not immediately applied, since the lower winding of this relay is energized through the front contact of the relay CR; but as soon as the relay CR is deenergized at the first active inductor, the brakes are automatically applied. If it is the lower winding of the relay BR which develops the open circuit, the brakes are applied automatically as soon as the time-element device starts and opens its contacts 123 upon passing the first active inductor.

If the circuit for the magnet TM of the time-element device should open by itself, the balance wheel is released and after some oscillation assumes the intermediate position with its contacts 123 open. The brakes are not immediately applied, because the relay BR is held up by its energizing circuit through the front contacts of the relay CR; but upon the dropping of the relay CR at the first active track inductor, the brakes are immediately applied and maintained applied, inasmuch as the relay CR can not be restored, its pick-up circuit being open at the contacts 123.

If the circuit for the change-over magnet CM should for any reason be broken, the permissive speed limits for freight trains would be enforced regardless of whether the apparatus is set for freight or passenger service, so that the lower speed limit of the two is enforced.

In short, the various circuits of the carried devices are such that if the current flow therein is entirely interrupted, or is reduced to a predetermined and dangerous extent, an automatic application of the brakes is sooner or later effected, or a lower speed limit is enforced.

Having shown the present invention in a rather specific manner, it should be understood that this has been done for illustrative purposes only, rather than with the view of

showing the scope of the invention. For instance, the car-carried circuit arrangement illustrated in Fig. 11 may be used to apply the brakes by mechanism which is entirely independent of the engineer's brake valve as well as to actuate the brake valve actuator illustrated. Also, although a single pair of spaced inductors has been shown, the second of which is automatically controlled only, it is to be understood that there are preferably two or more such pairs for each block, and that the first inductor may also have a controlling coil, if desired, although herein shown and described without a coil for purposes of economy. Similarly, both of the trackway elements of a pair may be permanently active in certain sections of the trackway to enforce a restriction in the speed under clear traffic conditions. These trackway devices may also be controlled manually from a signal tower as well as automatically by trackway circuits in conformity with well-known practice at the entrance to and through interlocking territory. It is, therefore, desired to be understood that various changes and modifications may be made to adapt the invention to the various types of railway systems encountered in practice, without departing from the scope or the idea of means underlying the invention.

What is desired to be secured by Letters Patent of the United States, is:—

1. In a combined manual and automatic brake valve, the combination of the usual engineer's brake valve comprising a casing of general cylindrical shape having a cap of smaller diameter bolted thereto, an automatically operated valve actuator having a downwardly extending web partially surrounding said cap bolted to said casing, and a handle projecting from said actuator and cooperating with the rotary valve in said casing and engaging the usual notches in said cap.
2. In a combined manual and automatic brake valve, the combination of the usual engineer's brake valve comprising a casing of general cylindrical shape having a cap of smaller diameter bolted thereto, an automatically operated valve actuator having a downwardly extending web partially surrounding said cap bolted to said casing, and a handle projecting from said actuator and cooperating with the rotary valve in said casing and engaging the usual notches in said cap, said handle being at times automatically disconnected from the rotary valve.
3. In a combined manual and automatic brake valve, the combination of a rotary valve, a handle for controlling said valve connected thereto by a disengageable latch, automatic means for operating said valve, means operated to disengage said latch when said valve is automatically operated, and means manually operable which if placed in one position causes said last mentioned means to be ineffective.
4. An engineer's brake valve for controlling the usual pneumatic brakes of railway trains comprising, the usual engineer's brake valve casing, a rotary valve in said casing, a housing bolted on top of said casing, a handle projecting from said housing, an insulating ring in said housing supporting a contact segment and directly connected to said handle, and contact fingers supported by said housing but insulated therefrom and adapted to cooperate with said contact segment.
5. In a braking system, the combination with an engineer's brake valve, a handle disengageably connected to the rotary valve of said brake valve, and means operated automatically for moving said rotary valve to the service position and simultaneously disconnecting said handle from said rotary valve, said means including a differential piston mechanism having fluid pressure acting on both sides of said piston, whereby the release of pressure from one side of said piston effects operation of said rotary valve.
6. A combined manual and automatic brake valve for controlling the usual pneumatic brakes of railway trains comprising, the usual engineer's brake valve casing, a rotary valve in said casing, a handle for operating said rotary valve manually, automatic means for moving said rotary valve to the brake applying position, and manually operable means which if placed in one position causes said handle to be disconnected from said rotary valve while said valve is being automatically operated and when in the other position causes said handle to be permanently locked to said rotary valve.
7. A combined manual and automatic brake valve for controlling the usual pneumatic brakes of railway trains comprising, the usual engineer's brake valve casing, a rotary valve in said casing, a handle for operating said rotary valve manually, automatic means for moving said rotary valve to the brake applying position, manually operable means which if placed in one position causes said handle to be disconnected from said rotary valve while said valve is being automatically operated and when placed in another position causes said handle to be permanently locked to said rotary valve, and means for locking said manually operable means in one position.
8. A time element device for train control systems of the time-distance interval type comprising, an oscillatable time element shaft having an inertia wheel and a coil spring thereon, whereby it will be caused to oscillate at a definite period when initiated, electrically operated means for initiating said device, and means conveniently

operated for changing the period of oscillation of said time element shaft to a predetermined different period.

9. A time element device for automatic train control systems of the time-distance interval type comprising, a time element shaft having an inertia wheel thereon, electrically controlled means for normally holding the time element shaft in an extreme position, spring means urging said shaft to an intermediate position, whereby if said electrically controlled means is released the shaft will oscillate at a predetermined period, contacts opened and closed by the oscillation of said shaft, and controllable means for changing the period of oscillation of said shaft.

10. A time element device for automatic train control systems of the time-distance interval type comprising, a time element shaft having an inertia wheel thereon, electrically controlled means for normally holding the time element shaft in an extreme position, spring means urging said shaft to an intermediate position, whereby if said electrically controlled means is released the shaft will oscillate at a predetermined period, contacts opened and closed by the oscillation of said shaft, a weight comprising magnetizable material adapted to rest upon and frictionally engage said inertia wheel, and electrically controlled means for raising said weight from said inertia wheel, whereby the time element shaft will oscillate at two different periods dependent upon whether or not said weight rests on said inertia wheel.

11. A time element device for automatic train control systems of the time-distance interval type comprising, a time element shaft having an inertia wheel thereon, electrically controlled means for normally holding the time element shaft in an extreme position, spring means urging said shaft to an intermediate position, whereby if said electrically controlled means is released the shaft will oscillate at a predetermined period, contacts opened and closed by the oscillation of said shaft, a weight adapted to rest upon and frictionally engage said inertia wheel, whereby the time element shaft will oscillate at different periods depending on whether said weight rests upon said inertia wheel, and manually operable means for at times lifting said weight from said inertia wheel.

12. A time element device for automatic train control systems of the time-distance interval type comprising, a time element shaft having an inertia wheel thereon, electrically controlled means for holding the shaft in one extreme position, means for biasing said shaft to an intermediate position, whereby if said electrically controlled means releases said shaft the shaft oscil-

lates for a time and finally assumes the biased position, and means adapted to be controlled from a distance for resetting said time element shaft back to its said extreme position.

13. A time element device for automatic train control systems of the time-distance interval type comprising, a time element shaft having an inertia wheel thereon, electrically controlled means for holding the shaft in one extreme position, means for biasing said shaft to an intermediate position, whereby if said electrically controlled means releases said shaft the shaft oscillates for a time and finally assumes the biased position, and means including a piston adjacent said shaft and a valve only accessible from the ground for resetting said time element shaft back to its normal position.

14. An automatic train control system comprising, a plurality of electro-responsive devices located at an accessible place on a railway vehicle and including a brake control device, said devices being adapted to control the usual air brakes of the vehicle and if once actuated remaining in its active condition until restored, said device being controlled inductively through an intervening air gap in accordance with traffic conditions ahead, and pneumatic means controlled by a manually operable valve only accessible from the ground for restoring said brake device to its normal inactive condition.

15. An automatic train control system comprising, a plurality of electro-responsive devices located at an accessible place on a railway vehicle and including a brake control device, said devices being adapted to control the usual air brakes of the vehicle and if once actuated remaining in its active condition until restored, said device being controlled inductively through an intervening air gap in accordance with traffic conditions ahead, and pneumatic means controlled by a manually operable valve only accessible from the ground for restoring certain of said devices when placed in its abnormal position but permitting the restoration of said brake control device only after said valve has been returned to its normal position, whereby the brake control device may be restored but may not be permanently held in the restored position by leaving said valve in its abnormal position.

16. A time element device for automatic train control systems of the time-distance interval type comprising, a time element shaft, an inertia wheel rotatably supported on said shaft but frictionally fastened thereto through an intervening friction clutch, electrically controlled means including an armature on said shaft for normally holding said shaft in a predetermined extreme position, and means for biasing said shaft

to an intermediate position whereby when said electrically controlled means momentarily releases said armature said shaft completes a cycle of oscillation in response to 5 the bias of said spring and the inertia of said inertia wheel.

17. In an automatic train control system, the combination of a control device which may be either manually or automatically 10 operated to apply the brakes of the usual air-brake system and which may be manually adjusted so that it will either make an unpreventable brake application which the engineer can not prevent, or a permissive 15 brake application which may be opposed and prevented by the engineer when the device is automatically controlled, a time element device and associated mechanism adapted to control said brake control device to operate 20 the same in the event two successive control influences are transmitted from spaced trackway devices along the trackway in less than the time required for the time element device to complete its cycle of operation, and 25 manually operable means for simultaneously changing the brake control device from an unpreventable to a permissive automatic brake control device and for increasing the time required for said time element device 30 to complete its cycle of operation, whereby a more restrictive speed limit is set up when the brake control device is adjusted to cause a permissive brake application, and a less restrictive speed limit is set up by the same 35 spaced control points when the brake control device is adjusted to cause an unpreventable brake application.

18. In an automatic train control system, the combination of the usual engineer's brake 40 valve, an actuator for operating said valve, a handle for manually operating said valve, a time element device and associated apparatus for operating said actuator if two control influences are transmitted from a pair 45 of spaced track devices in less than the time constant of said time element device, and manually operable means which if in one position causes said handle to be operatively disconnected from said brake valve when an 50 automatic actuation of the brake valve takes place and simultaneously therewith sets up a small time constant for said time element device and when placed in the other position permanently locks said handle to said valve and sets up a larger time constant.

19. In a braking system of the type in which if the brake pipe is vented an application of the brakes occurs, the combination of an engineer's brake valve having a handle, 60 means for automatically disconnecting said handle from said brake valve and moving said valve toward the brake applying position, said means including two opposing pistons of different size normally having fluid pressure acting thereon, whereby the release 65

of pressure from the larger piston causes the pistons and valve to move in response to the pressure acting against the smaller piston.

20. An automatic train control system 70 comprising, a brake control device adapted to be adjusted for causing brake applications suitable for freight and passenger service respectively, speed restricting means adapted to be adjusted to restrict the speed 75 in a manner suitable for freight and passenger service respectively, and manually operable means for simultaneously changing the adjustment of said brake control device and said speed restricting means from freight to 80 passenger service, or vice versa.

21. Car-carried apparatus for automatic train control systems comprising, a car-carried core of magnetic material of general inverted U-shape, a highly energized 85 primary winding on one of the legs of the core, a normally energized brake control device which if deenergized causes an automatic application of the brakes, a circuit including said primary coil and said brake control device in series and a source of energy, a control relay, a secondary coil on the other leg of said core connected in series with said control relay, said control relay and secondary coil being connected in multiple with said primary coil, whereby the control relay is energized by the potential drop across said primary coil and shunting of said primary coil causes deenergization of said control relay. 95

22. An automatic train control system of the type in which control influences are transmitted through an intervening air gap inductively comprising, an electro-pneumatic brake control device adapted to automatically apply the brakes of the usual air-brake system if deenergized, a plurality of normally energized electro-responsive devices and associated mechanism for causing automatic actuation of said brake control device under predetermined conditions, and a cutout device for automatically deenergizing said brake control device and electro-responsive devices when the main reservoir pressure of said air-brake system falls below a predetermined value. 105

23. A time element device for automatic train control systems comprising, a time element shaft having an inertia wheel thereon, a coil spring having one end connected to 110 said shaft, an anchor for positioning the other end of said spring so as to urge said shaft into a predetermined position, electrically operable means for normally holding said shaft in a position to tension said spring 115 which if actuated allows said shaft to assume an intermediate position, and resetting means for temporarily moving said anchor to a position to allow said shaft to move to its normal position, thereby allowing the 120 125 130

electrically operable means to again hold said shaft in its normal position.

24. Car-carried apparatus for automatic train control systems of the time-distance interval type comprising, a time element device of the balance wheel type having a shaft biased to an intermediate position but held in one extreme position by suitable normally energized electrically operable means, a control relay momentarily de-energized upon the reception of a control influence from the trackway, and means for permanently deenergizing said electrically operable means if said control relay is de-energized twice in less than a predetermined time, whereby said time element shaft assumes its intermediate position if two successive influences are received in less than a predetermined time.

25. Combined manual and automatic brake applying mechanism for air brake systems of the type in which a brake pipe is normally charged with fluid pressure and wherein venting of the brake pipe effects a brake application, a brake applying device, manually operable means for effecting movement of said device to its brake applying position in which position it vents said brake pipe, automatic means for rendering said manually operable means ineffective and for operating said device to a brake applying position including two opposite pistons of different size normally having fluid pressure acting thereon, whereby the release of pressure from the larger piston effects operation of said automatic means.

26. In a braking system, the combination with an engineer's brake valve having a rotary valve therein; mechanism including a handle for operating said rotary valve to the release, the running and a brake applying position; automatic means for operating said rotary valve including two opposing pistons of different size normally having fluid pressure acting thereon, whereby the release of pressure from the larger piston causes the automatic means to be operated; said mechanism being constructed so as not to permit said rotary valve to be moved toward the release position manually when it is automatically operated to a brake applying position even though the force produced by the automatic means is less than that exertable by the engineer.

27. In a manually and automatically operable brake valve, the combination of a housing having a seat therein, a rotary valve on said seat, a cap for said housing through which the stem of said rotary valve projects, a handle loosely mounted on said stem, an automatically operable member mounted loosely on said stem above said handle, a latch for normally locking said handle to said stem, and means associated with said member for unlatching said handle and mov-

ing said valve to a brake applying position if said member is operated.

28. In an engineer's brake valve, the combination of a valve stem, a handle mounted for movement about the axis of said valve stem, lugs projecting from said stem and handle whereby the valve stem may be operated to a brake applying position by said handle, latching means on said stem and handle whereby said stem may be operated to a brake releasing position by said handle, and means automatically operated mounted above said handle for operating said stem to a brake applying position and unlatching said latching means.

29. A brake valve operator comprising, a member pivoted about a vertical axis and operatively connected to the rotary valve of an engineer's brake valve, a spring pressed latch supported by said member also pivoted about a vertical axis, manually operable means movable about a vertical axis locked to said member by said latch, and power operated means operable about a vertical axis adapted to unlock said latch and engage said member when moved toward its active position to move the rotary valve to a brake applying position.

30. In a manually and automatically operable brake valve, the combination of a rotary valve having a handle operatively connected thereto, automatic means for operating said valve, and separate means which if held by the engineer prevents said automatic means from operating said rotary valve.

31. In a manually and automatically operable brake valve, the combination of a rounded casing having notches at its periphery, a rotary valve in said casing having a handle projecting therefrom, said handle having a spring latching means for engaging said notches, automatic means for operating said valve, and means operable by the engineer for more firmly latching said handle to said casing, whereby the engineer by operating said last mentioned means may prevent said automatic means from operating said rotary valve.

32. Car-carried apparatus for automatic train control systems comprising, a normally energized normally inactive brake control device, means for causing actuation of said brake control device if the speed of the vehicle is excessive for prevailing traffic conditions ahead, and pneumatically operable means for restoring said brake control device to its inactive condition, said pneumatically operable means including a valve accessible only by a man standing on the ground and which must be operated to its restoring position and then returned to its normal position in order to effect restoration of said brake control device.

33. Car-carried apparatus for automatic train control systems, comprising, a nor-

5 mally energized normally inactive brake control device, means for causing actuation of said brake control device if the speed of the vehicle is excessive for prevailing traffic 10 conditions ahead, and pneumatically operable means for restoring said brake control device to its inactive condition, said pneumatically operable means including a valve accessible only by a man standing on the 15 ground and which if operated restores said brake control device to normal, and circuit closing means associated with said valve which requires said valve to be returned to its normal position in order to permit the 20 train to proceed.

34. An automatic train control system comprising, train control means adapted to be adjusted for setting up restriction suitable for freight and passenger service respectively, brake control apparatus for causing an unpreventable brake application which the engineer cannot prevent or a 25 preventable brake application which the engineer can prevent depending on the condition of suitable selecting means, manually

operable means for adjusting said train control means and said selecting means, said manually operable means being so arranged that said brake control apparatus can only be adjusted to cause a preventable brake application when restrictions suitable for freight service are set up. 30

35. A brake valve operator comprising, a member pivoted about a vertical axis and operatively connected to the rotary valve 35 of an engineer's brake valve, a spring pressed latch supported by said member also pivoted about a vertical axis, manually operable means movable about a vertical axis locked to said member by said latch, a gear 40 operable about a vertical axis adapted to unlock said latch and engage said member to move said brake valve to a brake applying position when rotated in the brake applying direction of said engineer's brake valve, a 45 rack operatively engaging said gear, and pneumatic means for operating said rack.

In testimony whereof I hereby affix my signature.

CHARLES S. BUSHNELL.
